UNITED STATES PATENT OFFICE.

WILLIAM F. GROENE, OF CINCINNATI, OHIO, ASSIGNOR TO THE R. K. LEBLOND MACHINE TOOL COMPANY, OF CINCINNATI, OHIO, A CORPORATION OF OHIO.

CLUTCH.

1,288,563.

Specification of Letters Patent. Patented Dec. 24, 1918.

Application filed June 12, 1917. Serial No. 174,210.

To all whom it may concern:

Be it known that I, WILLIAM F. GROENE, a citizen of the United States, residing at Cincinnati, in the county of Hamilton and State of Ohio, have invented an Improvement in Clutches, of which the following description, in connection with the accompanying drawings, is a specification, like characters on the drawings representing like parts.

The invention hereinafter described relates to clutches for connecting pulleys to shafts and for other purposes.

One of the objects of the invention is to provide simple and effective operating means for expanding a split ring into gripping engagement with a pulley.

Another object is to provide an operating means which may be quickly and easily assembled and held in its operative relation with respect to the split ring.

Still another object is to provide simple and effective means for lubricating the pulley and holding the expansion ring in proper position axially of said pulley.

The character of the invention may best be understood by reference to the following description of one good form of the invention shown in the accompanying drawings, wherein:

Figure 1 is a vertical section taken on the line 1—1 of Fig. 2, showing a pulley and clutch mechanism embodying the invention;

Fig. 2 is a vertical transverse section taken on the line 2—2 of Fig. 1;

Fig. 3 is a detail of the end portions of the split ring and the device between the same, for expanding the ring;

Fig. 4 on an enlarged scale, is a vertical section taken on the line 4—4 of Fig. 3;

Fig. 5 is a sectional detail showing the position of the cam in expanding the ring; and

Fig. 6 is a perspective view of the cam and the locking member coöperating therewith to limit movement of said cam transversely to the plane of the ring.

Referring to the drawings: The mechanism shown therein as embodying the invention comprises a shaft 1 having a sleeve 3 thereon provided with a bearing portion on which is journaled the hub 5 of a pulley 7.

A hub 9 at one end of said sleeve has resilient arms 11 projecting therefrom, in the present instance of the invention said

arms being formed with a compound curve. These arms serve to support a split ring, in the present embodiment of the invention composed of two sections 13. The ring sections may be located within and be adapted to expand into frictional engagement with a circumferential flange 15 projecting laterally from the rim of the pulley.

To expand the ring sections, devices may be provided at diametrically opposed points 65 between adjacent ends of the ring sections, and since these devices are similar, a description of one will suffice for both. In the present instance of the invention, this device comprises a cam element 17 in the form of a 70 stud journaled in a recess 19, in one of the opposed ends of the split ring and having a slabbed-off face 21 adapted to expand the ring as more fully hereinafter described.

Coöperating with the cam is a locking 75 member typified herein in the form of a plate 23 located between the opposed ends of the split ring. This locking member presents a flat face 25 opposed to the flat face of the cam element, the construction being 80 such that as the cam is rocked, its flat face will wipe along and react against the plate, thereby bringing a longer radius of the cam into play and causing the ring to be expanded from its position shown in Fig. 4 to 85 its position shown in Fig. 5.

To prevent movement of the cam element or stud transversely to the plane of the ring, the opposed flat faces of the cam element and locking member are provided with inter-engaging elements, conveniently in the form of a tongue 27 on one, fitting a groove 29 on the other. The tongue and groove are disposed radially of the ring and therefore will permit rocking of the cam element to 90 expand the ring, but at the same time will prevent relative movement of the cam element and locking member transversely of the ring.

To limit movement of the locking member 100 transversely of the ring, it may have a flange or lip 33, Fig. 6, projecting therefrom and adapted to engage the end 35 of the cam element and the rear face of one of the ring sections. A flange 36 on the cam 105 may engage the front face of said ring section and thereby limit movement of the cam and locking member in the opposite direction.

To limit movement of the locking mem- 110

ber radially of the ring, it may have a projection 35 adapted to enter a recess 37 in the end of the split ring opposite the end in which the cam element is journaled. The 5 recesses receiving the cam element and locking member may conveniently constitute parts of a single bore formed in the opposed ends of the ring sections.

To operate the cam element, it may have 10 a bell crank 39 integral therewith or otherwise connected thereto, having an arm projecting inward toward the shaft 1 referred to, and provided with a bolt 41 adapted to engage a sliding cone 43, Fig. 1, mounted on 15 said shaft. The other arm of the bell crank carries a weight 45 which tends to move outward by effect of centrifugal force thereon and thereby maintains the bolt in contact with the cone. The bolt may be adjusted relatively to its arm to vary the pressure of the clutch.

The parts of the device for expanding the ring may be very quickly and easily assembled therewith. To accomplish this, it is merely necessary to slide the cam into its recess and then slide the locking member radially of the ring into place between the opposed ends of the ring sections, said ends being spread apart sufficiently for this purpose. Upon release of said ends, the projection 35 on said locking member will snap into its recess. Thus, the cam element is locked against movement transversely of the ring merely by the assembly of said element 30 and the locking member with the ring, as described. After the parts are thus assembled, they are securely maintained in their operative relation without danger of dislocation, because there are no parts to work 35 loose and get out of place.

To lubricate the bearing surface of the pulley and sleeve, an oil reservoir 47, Fig. 1, may be mounted on the shaft 1 and be threaded on a reduced end 49 of the sleeve. The hub 9 may be formed to engage one end 45 of the hub 5 of the pulley to limit movement of the latter axially of the shaft in one direction and the oil reservoir may have an end 51 for engagement with the opposite end of the hub of the pulley to limit movement thereof axially in the opposite direction. Thus, the hub of the clutch mechanism and the oil reservoir in serving their dual functions, contribute to the compact, simple organization of the mechanism.

To conduct the oil from the reservoir to the bearing surfaces, ports 53 may be provided in the sleeve axially thereof and communicate with grooves 55 opening toward the bearing surface of the pulley. Suitable wicks (not shown) may extend from the reservoir through said ports into said grooves to conduct the oil to the bearing surfaces by capillary attraction.

65 To secure the sleeve to the shaft, the oil

reservoir may be provided with a thick wall 57 having one or more screws 59 threaded radially therethrough and adapted to engage the shaft. The oil reservoir may be filled through an inlet 61 in the wall 57 and 70 closed by a suitable stopper.

In use, it may be supposed the pulley is driven by a belt and it is desired to connect the pulley to the shaft so as to drive the latter therefrom. To accomplish this, the 75 cone 43 is shifted to the left, Fig. 1, thereby rocking the bell cranks and the cam studs thereon from their position in Fig. 4 to their position shown in Fig. 5. As a consequence, the flat faces of the cams will 80 slip along and react against the flat faces of the locking members and thereby expand the ring into the flange 15 of the pulley. Since the ring is mounted on and rotates with the sleeve which is fast on the shaft, 85 upon being connected with the pulley it will cause rotation of said shaft.

When it is desired to release the clutch, the cone 43 is shifted to the right of Fig. 1 and the effect of centrifugal force on the 90 bell cranks will cause them to rock in a direction to return the cam elements to their position shown in Fig. 4. This movement is assisted by the resilience of the arms 11 of the ring sections which tend to retract the 95 latter from the flange of the pulley.

It will be understood that the invention is not limited to the specific embodiment shown, but that extensive deviations may be made therefrom without departing from the spirit 100 and scope of the appended claims.

What is claimed is:—

1. In a clutch, the combination with a split ring having recesses in opposed ends thereof, of a cam element journaled in one 105 of said recesses for expanding the ring, means to operate said cam element, and a member in the other recess for limiting movement of said cam element transversely to the plane of said ring.

2. In a clutch, the combination with a split ring having recesses in the opposed ends thereof, of a cam element mounted in one of said recesses, and a plate mounted in the other recess, said cam element and plate 115 having interengaging means for limiting relative movement thereof transversely to the plane of said ring.

3. In a clutch, the combination with a split ring having opposed ends, of a cam 120 element mounted in one of said ends, a locking member between said ends, said cam member and locking member having tongue and groove means for limiting movement of said cam element transversely to the plane of 125 said ring.

4. In a clutch, the combination with a split ring having opposed ends, of a cam element mounted in one of said ends, a locking member between said ends, said cam 130

member and locking member having means limiting relative movement thereof transversely of said ring, and means limiting movement of said locking member radially 5 and transversely of said ring.

5. In a clutch, the combination with a split ring having recesses in opposed ends thereof, of a cam element journaled in one of said recesses, a locking member projecting into the other recess to limit the same radially of said ring, and means to limit movement of said member transversely of 10 said ring, said cam element and locking member having interengaging means to limit 15 relative movement thereof transversely to said ring.

6. In a clutch, the combination with ring sections, of a hub, resilient arms connecting said sections with said hub, cam elements 20 for spreading opposed ends of said sections, locking members adapted to be snapped between said ends to secure said elements in operative position, and means for rocking said elements.

25 7. In a clutch, the combination with a ring having opposed ends, a cam element for spreading said ends, a locking member adapted to be snapped between said ends to

secure said cam element in operative position with respect to said ends, and means 30 for operating said cam element.

8. In a clutch, the combination with ring sections, of a hub, resilient arms connecting said sections with said hub, cam elements for spreading said ends, locking members 35 adapted to be snapped between said ends to secure said elements in operative position, and bell cranks for rocking said cam elements having weighted arms and operating arms. 40

9. In a clutch, the combination of a circular member, a split ring mounted therein having opposed ends with a bore formed partly in each of said ends, a plate or equivalent member over the part of said bore in 45 one of said ends, a stud having a flat face for wiping engagement with said plate or member and a rounded portion seated and adapted to rock in the other part of said bore, and means to rock said stud to expand said ring into clutching engagement with said circular member. 50

In testimony whereof, I have signed my name to this specification.

WILLIAM F. GROENE.
